F. LAFIN

FLOOR DRAIN

Filed August 25, 1924

UNITED STATES PATENT OFFICE.

FRED LAFIN, OF CHICAGO, ILLINOIS.

FLOOR DRAIN.

Application filed August 25, 1924. Serial No. 733,905.

To all whom it may concern:

Be it known that I, FRED LAFIN, a citizen of the United States, residing at Chicago, in the county of Cook and State of Illinois, have invented certain new and useful Improvements in Floor Drains, of which the following is a specification.

This invention relates to improvements in cellar-drains or devices adapted for the prevention of overflow of water into basements from sewers, catch-basins and the like.

A large number of devices for automatically preventing back-flow of water into basements, cellars and the like are offered on the market and are extensively used, nearly all such devices being more or less similar to back-pressure or check-valves. Practice has demonstrated that they cannot be relied upon to operate effectively for the reason that water passing from the cellar or basement into the drain and reversely, carries all sorts of solids which become lodged upon the valve-seat of the device and prevent effective closure of the valve so that in the majority of instances the automatic devices serve only to restrict without preventing back-flow.

The object of my invention is to provide manually operable means for effectually preventing back-flow into basements or cellars, which may be used independently of or in conjunction with such automatic devices and will serve to permit the user to observe conditions with respect to back-flow, as herein-after fully described.

Suitable embodiments of the invention are illustrated in the accompanying drawings, wherein:—

Fig. 1 is a central vertical section of a cellar drain constructed in accordance with the invention.

Fig. 2 is a similar view of another embodiment of the invention.

Fig. 3 is a plan section on the line 3—3 of Fig. 2.

Fig. 4 is a view partly in section and partly in elevation of a slightly modified embodiment of the construction shown in Fig. 2.

In its simplest and preferred embodiment, my invention consists of an internally threaded sleeve or floor element 1 provided with an external annular flange 2 and an annularly enlarged mouth portion 3, the upper face of the latter being adapted to be disposed flush with the (usually concrete) floor of the basement or cellar; the flange

2 being adapted to be embedded in the concrete to thus firmly anchor the element 1. The lower end of the latter is adapted to be connected, either by the internal threads 60 thereof or by other suitable and well known means, with the intake end 4 of a trap, leading to the soil pipe through which water passes from the floor into the sewer, the upper end of the trap-mouth 4 providing an annular shoulder upon which a strainer plate, common in this art, may be mounted. The element 1 may constitute a part of or be associated with the casing of a back-pressure or check-valve interposed between the 70 trap and the mouth of said element 1 or its equivalent.

The flat surface bordering the mouth or intake end of the element 1 constitutes a suitable seat for the soft rubber gasket 5 interposed between said surface and the annular flange 6 of a cap element 7 having an externally threaded lower portion for engaging the internal threads of the element 1. Said cap element 7 is further formed 80 with a plane peripheral portion 7' between the peripheral threads thereof and the lower face of the flange 6. The gasket 5 surrounds the portion 7'.

In the embodiment of Fig. 1, the cap element includes the vertical tube 8 which is shown as threaded into a threaded central opening in said cap but may be otherwise suitably associated with the latter. Said tube 8 will be of such length as to extend 90 above the maximum possible water level capable of being attained in the basement or cellar by back-flow and will be determined by local conditions.

In the embodiments shown in Figs. 2 to 4 95 inclusive, the element 9, corresponding to the element 1 of Fig. 1, is provided between its ends with a lateral branch 10 terminating in a threaded mouth portion 11 for connection with either a stand pipe 12, corresponding to the pipe or tube 8 of Fig. 1 or a laterally extending pipe 13 associated at its other end with the stand-pipe 14 disposed at a distance from the element 9, the latter equipped with the sealing cap 15.

The function of the several embodiments shown is substantially the same, the closure cap 7 or 15 being mounted in place to prevent back-flow during periods, as at night, when the basement or cellar is wholly unoccupied or free from observation and back-flow is apt to result from heavy rains.

It is true of the great majority of basements equipped with floor-drains that the latter function only when it is desired to wash the floors or to drain out water spilled on the floor during laundering or the like, there being only few instances where the drains function continually to drain off seepage or leakage. Where the latter is but slight, it may be permitted to accumulate around the drain and let off at intervals, this being preferable to flooding by back-flow of sewage so frequently occurring in many cities. Hence, the ordinary cellar drain may be sealed so far as its drainage function is concerned, except at such intervals as it may be necessary to open it to drain off flush or wash-water or the like.

It is desirable, however, that it should be known before opening the drain that there will be no in-rush of water due to back-flow. The stand-pipes 8, 12 or 14 permit observation in advance of removal of the cap, it being obvious that the stand-pipe used may be ordinarily sealed at the top to prevent ingress of sewer-gas to the basement or cellar following evaporation of water in the trap due to long disuse of the drain, a condition that is not uncommon.

If the closure element 7 or 15 is in place and back-flow from the soil pipe occurs, it will occasion no more than the rising of back-flow water into the stand-pipe to a certain level, and, upon relief from the condition causing such back-flow, the water in the stand-pipe will return into the soil-pipe, but

so long as said condition continues, water will stand in the stand-pipe and warn against unsealing or opening the floor drain.

I claim as my invention:—

A floor drain comprising a vertically disposed internally threaded sleeve open at each end provided between its ends and at its upper end with external annular flanges, adapted to be embodied in the concrete of a floor and with the upper face of the upper flange substantially flush with the floor surface, said sleeve adapted for threaded connection with the mouth portion of a trap to thereby provide an internal annular shoulder within and between the ends of said sleeve, said sleeve formed with an integral lateral extension thereby providing a lateral outlet therefor between the ends thereof, a stand-pipe associated with said outlet and extending above the maximum probable flood level of back-flow water, an element having an externally threaded lower portion and an annular flange above said threaded portion and spaced from said threads by a plane peripheral portion, said element adapted for removable association with the upper portion of said sleeve for preventing back-flow of water through said sleeve in time of flood, and a flexible gasket surrounding said plane peripheral portion and disposed between the lower face of said last-named flange and the top face of the upper flange of said sleeve for providing a water-tight joint.

FRED LAFIN.
